MAGNETICALLY FOCUSED ELECTRON GUN

Marion E. Hines, Summit, N. J., assignor to Bell Telephone Laboratories, Incorporated, New York, N. Y., a corporation of New York

Application June 17, 1950, Serial No. 168,803

13 Claims. (Cl. 315—4)

1

This invention relates to electron discharge devices and, more particularly, to electron guns for high current electron beam devices.

In general, in a number of known general types of electron beam discharge devices, high current beams are imminently desirable. In some devices, the desired high current may be realized by utilization of beams of substantial diameter. In others, however, for example, in high frequency devices of the traveling wave type, a requisite for optimum operation is that the beam be of very small diameter and, further, that the diameter remain substantially constant over a long path. Ways of maintaining the beam diameter small and substantially constant between the inlet and outlet ends of a given region have been suggested in the art. However, there still remains the problem of obtaining a beam of the requisite or desired high density at the point of injection into the given region.

Known electron guns involving conventional focusing methods suffer a serious limitation due to space charge effects. Specifically, forces resulting from space charge cause a divergence of the beam and the greater the current density, the greater these forces, and the greater the tendency toward beam divergence. Thus, in known devices in general, a choice or compromise must be made between current density in the beam and beam diameter.

One general object of this invention is to enable realization of high current densities in an electron beam concomitantly with substantially minimum beam diameter. More specifically, one object of this invention is to enable attainment of maximum current density in a beam of given diameter, or, viewed in another way, to attain a minimum beam diameter for a given current density.

Another object of this invention is to provide a magnetically focused electron gun for producing a small diameter beam, which comprises a large area cathode and, consequently, is capable of projecting a high current, intense electron beam.

A further object of this invention is to nullify space charge repulsion effects in an electron beam.

Still another object is to improve electron guns generally.

In accordance with a feature of this invention, an electron beam of circular cross section is projected through a circular aperture in one element of a magnetic system, which creates a radial magnetic field in the region of said aperture having a magnetic field component thereof perpendicular to the flow of said beam. This field component is greatest at the periphery of said aperture and is zero at the center of said aperture. The electron beam is thus given a

2

rotating motion. The magnetic lines of force are then converged in a substantially parabolic manner. The rotating electron beam, which has been focused to form a converging conical-shaped beam having the same axis as the magnetic field, is held within that shape by the force of its interaction with the converging magnetic field, which is just great enough to supply the radial accelerating force of the rotating beam and to nullify the space charge effects in the electron beam.

A feature of the invention pertains to a converging conical-shaped rotating electron beam in conjunction with a converging paraboloidal magnetic field, which permits the beam from a large cathode to be focused to a smaller diameter than has heretofore been possible.

The above-mentioned and other objects and features of the invention will be more clearly understood from the following detailed description when read in conjunction with the drawings, in which:

Fig. 1 is a view, mainly in section, of a discharge device including an electron gun illustrative of one embodiment of the invention;

Fig. 2 is a diagram illustrating the magnetic field in the gun shown in Fig. 1;

Fig. 3 is a diagram illustrating the electrostatic field due to space charge; and

Fig. 4 is another diagram showing the various components of velocity of the electron beam.

Referring now to Fig. 1, the cathode 11 is heated by heater coil 12, which is energized by battery 5. The electron beam represented by dotted lines 13 is focused and accelerated by electrodes 14 and 15, the geometry of electrodes 14 and 15 being such that the electron beam 13 is of conical shape. Electrode 15 is maintained at ground potential, and electrode 14 is maintained at approximately —1500 volts by means of battery 6. Reference is made to United States Patent 2,268,197, issued December 30, 1941, to J. R. Pierce, wherein a similar geometry is discussed in detail. Electrode 15 is of a magnetic material having an aperture 16 therein through which the electron beam passes.

The magnetic field established between pole-pieces 15 and 17, as described hereinafter, has a radial component thereof perpendicular to the axis of said aperture 16 which causes the electron beam passing through to acquire an angular velocity. The magnetic lines of force between pole-pieces 15 and 17 have a paraboloidal shape having the same axis as the axis of the electron beam. The two pole-pieces 15 and 17 are separated and supported by a non-magnetic shield 18, and the pole-piece 17 is magnetically positive with respect to the pole-piece 15. As the electron beam flows from aperture 16 to aperture 19, there is an interaction between the

rotating electron beam and the magnetic lines of force. This interaction gives each rotating electron in the electron beam a negative radial acceleration, which, in effect, causes the beam to remain confined within a small cross-sectional area. The size of this area is determined by parameters such as the strength of the magnetic field, the density of the electron stream, electron volt energy of the electron stream, and the angular velocity of said rotating electron stream. These parameters will be defined more clearly by detailed analysis later herein.

It is noted that surfaces 40 and 41 of elements 34 and 15 comprise a paraboloidal surface except where envelope 10 separates elements 34 and 15. Similarly, surfaces 42 and 43 of elements 21 and 17 also form a paraboloidal surface. The focal points of these two paraboloidal surfaces are substantially coincident with the focal point of the conical-shaped beam, which would theoretically occur in the vicinity of aperture 19. These surfaces represent equipotential surfaces of the magnetic field existing therebetween. The flux generated between these two surfaces then will also have a confocal paraboloidal geometry with the focal point substantially coincident with the focal point of the converging electron beam. This field is represented in Fig. 2, wherein the equipotentials and the flux lines at a plane passing through the axis of the electron beam are shown. It is not essential that the surfaces 40, 41 and 42, 43 be perfect confocal paraboloids of revolution, since other curved surfaces will also produce similar magnetic flux fields which can be suitably utilized in obtaining a converging electron beam. However, in the preferred embodiment of the invention described herein, paraboloidal surfaces are used.

The intensity of the magnetic field increases as the beam becomes smaller in diameter, always, however, being of such intensity as to provide interaction forces sufficient to cancel the increased space charge forces of the electron beam and the increased centrifugal forces due to the rotational motion of the electron beam. This will become clearer from the mathematical analysis which will be presented hereinafter.

In the aperture 19 in the electrode 17, the magnetic field is weaker than it is within the non-magnetic element 18, thus allowing the electron beam to diverge until the electron beam flow becomes cylindrical in shape. Upon leaving the aperture 19, the electron beam, which is now uniformly cylindrical, enters a magnetic field which is substantially parallel to the flow of the electron beam and of sufficient strength to maintain the uniformly cylindrically-shaped electron beam as it travels through the helix 25. Electrode 28 constitutes the collector for the electron stream and is maintained at approximately -1000 volts. In this particular embodiment of the invention, the electron gun has been adapted to a traveling-wave tube of the type disclosed in the application of L. M. Field, Serial No. 704,918, filed October 22, 1946, now Patent No. 2,575,383, issued November 20, 1951.

The signal to be amplified is injected by means of wave guide 22 upon antenna 23, which is secured to cylindrical element 24 and to the helix 25, which is grounded through lead 29. The signal travels along the helix with approximately the same forward component of velocity as of the electron stream and is fed into wave guide 21 by means of antenna 26, which is secured to

5 4 a cylindrical element 31. The helix 25 is supported by rods 32.

Coil 33 generates the flux which flows in a path determined by magnetic element 34 across an air-gap to magnetic element 15 forming a converging paraboloidal field inside non-magnetic element 18, through magnetic element 17, through magnetic elements 21, and back to element 34. It is to be noted that magnetic fields having radial components are formed in apertures 16 and 19. Coil 35 generates a flux which flows through a path comprised of magnetic electrode 21, magnetic electrode 17, forming a magnetic field substantially parallel to the flow of the electron beam from element 24 to element 31, and back to magnetic material 36.

A fuller understanding of the operation of this invention may be obtained from the following mathematical analysis. Due to the particular type of magnetic and electrostatic fields presented in this invention, spherical polar coordinates will be used to describe the electron paths and the electric and magnetic fields.

The orientation of the coordinates is shown in Fig. 4. MKS practical units will be used. Some of the symbols used are defined below.

q charge density expressed in coulombs per unit solid angle per meter along the radius.

ρ charge density in coulombs per cubic meter.

η charge to mass ratio of the electron, 1.76×10^{11} coulombs per kilogram.

ϵ dielectric constant of vacuum,

$$\frac{1}{36\pi} \times 10^{-9}$$

35 farads per meter.

r radial coordinate used in the spherical polar coordinate system.

θ angular displacement of r from a reference line which is herein chosen to coincide with the axis of the electron beam.

ϕ angular displacement of r from a reference plane. The "dot" notation is used to indicate total time derivatives, r indicating dr/dt , and $\dot{r}$ indicating d^2r/dt^2 , etc.

40 It is to be noted the phrase "radial component" when used in connection with the mathematical analysis applies to the spherical polar coordinate system utilized herein.

The method of solution is indirect, in that an assumed set of conditions is shown to satisfy the equations of motion for small angles of convergence. The first assumptions are that the radial velocity is constant and independent of θ and that there are no motions in the ϕ direction. A magnetic field configuration is chosen whose radial component is inversely proportional to the radius as shown in Figs. 2 and 4. Such a field is described by the following equations:

$$B_r = \frac{B_1}{r} \quad (1)$$

$$B_\theta = -\frac{B_1}{r} \tan \frac{\theta}{2} \quad (2)$$

$$B_\phi = 0 \quad (3)$$

55 where B_1 is the magnitude of the radial component of the field at unity radius, B_r is the flux in the r direction, B_θ is the flux in the θ direction, and B_ϕ is the flux in the ϕ direction. This field is a solution of Laplace's equation. The magnetic flux lines and the magnetic equipotential surfaces conform to the surfaces of paraboloids of revolution, which have a common focus at the origin of coordinates.

5

It is also assumed that the cathode is shielded from the magnetic field and that all fields are axially symmetric. From Busch's theorem, the angular velocity $\dot{\phi}$ can be deduced for electrons at any point in the space. The theorem specifies that

$$\dot{\phi} = \frac{\eta\Phi}{2\eta r^2 \sin^2 \theta}$$

where Φ is the total magnetic flux in the positive r direction which passes through a surface bounded by a line of constant r and θ . For the magnetic field chosen,

$$\Phi = 4\pi r B_1 \sin^2 \frac{\theta}{2}$$

and

$$\dot{\phi} = \frac{\eta B_1}{2r \cos^2 \frac{\theta}{2}}$$

The velocity distribution of the electrons is further specified by a constant r velocity, and zero θ velocity, as summarized below.

$$r = -\sqrt{2\eta V_0}$$

$$\dot{\theta} = 0$$

$$\dot{\phi} = \frac{\eta B_1}{2r \cos^2 \frac{\theta}{2}}$$

If it is also assumed that a uniform radial current density exists over the cone, the electrostatic field configuration due to space charge can be found. For a conical conducting boundary such as element 18 shown in Fig. 1, the field within the beam is given by

$$E_r = 0$$

$$E_\theta = \frac{q}{\epsilon_r} \tan \frac{\theta}{2}$$

$$E_\phi = 0$$

where q is the charge density expressed in coulombs per unit solid angle per unit radius. This is a solution to Poisson's equation. The electrostatic equipotentials are cones whose apexes are at the origin of the coordinates. The electrostatic flux lines conform to the surfaces of spheres whose centers are at the origin of coordinates. This is shown in Fig. 3. The total current I in amperes carried within a cone bounded by an angle ψ is

$$I = 4\pi q \sqrt{2\eta V_0} \sin^2 \frac{\psi}{2} \text{ amperes}$$

There is now established a set of assumed conditions specifying the velocity distribution and the static fields. It remains to demonstrate that these conditions satisfy the equations of electron motion. These equations are

$$\ddot{r} - r\dot{\theta}^2 - \dot{\phi}^2 r \sin^2 \theta = -\eta [E_r + r\dot{\theta} B_\phi - r\dot{\phi} B_\theta \sin \theta] \quad (11)$$

$$2\dot{r}\dot{\theta} + r\ddot{\theta} - r\dot{\phi}^2 \sin \theta \cos \theta = -\eta [E_\theta + r\dot{\phi} B_\phi \sin \theta - r\dot{\phi} B_\theta] \quad (12)$$

$$2\dot{r}\dot{\phi} \sin \theta + 2r\dot{\theta}\dot{\phi} \cos \theta + r\ddot{\phi} \sin \theta = -\eta [E_\phi + rB_\theta - r\dot{\theta} B_\phi] \quad (13)$$

Substitution of the assumed values for the velocities, fields, and accelerations into these equations

yields exact identities for Equations 11 and 13. Equation 12 reduces

$$\frac{-\eta^2 B_1^2 \tan \frac{\theta}{2}}{2r} \left[\frac{\cos \theta}{\cos^2 \frac{\theta}{2}} \right] \approx \frac{-\eta q \tan \frac{\theta}{2}}{\epsilon_r} \frac{\eta^2 B_1^2 \tan \frac{\theta}{2}}{r} \quad (12)$$

Another substitution

$$q = -\frac{\eta \epsilon B_1^2}{2} \quad (14)$$

yields

$$\frac{-\eta^2 B_1^2 \tan \frac{\theta}{2}}{2r} \left[\frac{\cos \theta}{\cos^2 \frac{\theta}{2}} \right] \approx \frac{-\eta^2 B_1^2 \tan \frac{\theta}{2}}{2r}$$

This approaches an identity for small θ where the expression in the brackets may be considered equal to 1. It is very nearly an identity even for θ as large as 10 degrees where the ratio of cosines is .992. This discrepancy represents an unbalance of forces in the θ direction which is practically negligible for reasonably small θ on the order of 0-10 degrees. This means that the assumed velocity distribution is not quite correct for the outer electrons in a wide angle beam, but the discrepancy is negligible for reasonably small cone angles.

The substitution made above specified by Equation 14 was necessary to make Equation 12 become an identity. It specifies the magnetic field B_1 required for any degree of space charge q .

In accordance with this relation, the beam current within a bounding angle ψ , which is the maximum value of θ , may be expressed as

$$I = 2\sqrt{2\pi\epsilon\eta^{3/2}B_1^2V_0^{1/2}} \sin^2 \frac{\psi}{2} \quad (15)$$

This is the relation which relates beam current I , beam voltage V_0 , cone angle ψ , and the magnetic field at unity radius B_1 . This is the basic design equation for the region of conical electron flow.

In MKS units, I is expressed in amperes, V_0 in volts, and B_1 in Webers per square meter. It should be noted that B_1 is the magnetic field which would exist at a radius of 1 meter from the origin of the coordinate system, and the radial

component of magnetic field at any other radius is equal to B_1/r . It is to be further noted that V_0 is the potential at the beam axis and will ordinarily be slightly more negative than the potential of the shield electrode.

The potential V in the beam is a function of the angle θ only and is given by

$$V = V_0 - \int_0^\theta r E_\theta d\theta \\ = V_0 + \frac{2q}{\epsilon} \log \cos \frac{\theta}{2} \quad (17)$$

where V_0 is the potential at the beam axis. For small θ where

$\tan \frac{\theta}{2} \approx \frac{\theta}{2}$
is approximately equal to

$$\frac{\theta}{2}$$

Equation 8 may be approximated as

$$E_\theta \approx \frac{q\theta}{2\epsilon r}, (\theta \text{ small})$$

which is the same as Equation 17.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation 17 yields

$V = V_0 + \frac{q\theta^2}{4\epsilon r}$

which is the same as Equation 15.

Substitution of this value for E_θ into Equation

which gives

$$V \approx V_0 - \frac{q\theta^2}{4\epsilon} \quad (\theta \text{ small})$$

If the electrons were emitted from a cathode at zero potential, their kinetic energies must correspond to the space potential V , as expressed by the equation

$$r^2\dot{\theta}^2 + \dot{r}^2 + (r\dot{\phi} \sin \theta)^2 = 2\eta V$$

Substitution yields

$$2\eta V_0 + \frac{\eta^2 B_1^2 r^2 \sin^2 \theta}{4r^2 \cos^4 \frac{\theta}{2}} \approx 2\eta \left(V_0 - \frac{q\theta^2}{4\epsilon} \right)$$

which reduces to an identity for small θ if

$$q = -\frac{\eta \epsilon B_1^2}{2} \quad (14)$$

which is the condition required for satisfying the equations of motion. Thus, the type of electron flow necessary to realize this invention can be obtained from a unipotential cathode.

For the electrostatic field, we have postulated a cone-shaped conducting shell surrounding the beam. While this is necessary to obtain the simple field described, in an actual case, it will probably not make a great deal of difference if it is shielded by a cylindrical or other shaped electrode. For the cone-shaped boundary, the electrostatic fields will be oriented as shown in Fig. 3, wherein the equipotential surfaces are represented by the radial lines from the origin and the electrostatic field is represented by the arcuate lines.

The magnetic field configuration is shown in Fig. 2. Both equipotentials and flux lines conform to the surfaces of paraboloids of revolution, which have a common focus with the electron stream. The required field may be realized with paraboloidal pole-pieces of large size and may be approximated closely with smaller pole-pieces of other shapes. These shapes can be experimentally determined by the use of an electrolytic tank.

As discussed before, Fig. 1 shows a configuration of electrodes which produces this type of flow. At the left, there is a converging gun of generally conventional construction. The accelerating anode of this gun is made of a magnetic material of high permeability and is shaped to shield the internal parts of the gun from the magnetic field. As the beam passes through this anode, it enters the magnetic field rather suddenly, which gives the beam a twist, providing the initial ϕ velocity. The total input velocity determines the cone angle and fixes the origin of the coordinates used to describe the motion and the magnetic field. The origin is chosen so that the electrons do not have any velocity in the θ direction after they have entered the magnetic field.

It is to be understood that the specific embodiment of the invention herewith shown and described is to be taken as a preferred example of the same and that various changes in shape, size, and arrangement of parts may be resorted to and other applications may be made thereof without departing from the spirit and scope of the invention.

What is claimed is:

1. An electron discharge device comprising a first and a second spaced magnetic member having axially aligned apertures therein, means for producing a conically converging electron beam, means for projecting said beam through said

apertures, and means including said first magnetic member, and magnetic means for producing a magnetic field configuration between said spaced members whose magnitude in the direction along the axis is inversely proportional to the axial distance from the point toward which the beam converges.

2. An electron discharge device comprising a magnetic element having an aperture therein, means for projecting an electron beam through said aperture in the direction of the axis of said aperture, magnetic means coupled to said element for producing at said aperture a magnetic field having a radial component increasing from said axis, and means for focusing said beam at a pre-assigned region beyond said aperture, said last means comprising means for producing a paraboloidal magnetic field beyond said aperture and including said magnetic element and said magnetic means.

3. An electron discharge device in accordance with claim 2, wherein said focusing means also comprises a second magnetic element having a second aperture therein and positioned near the focal point of said electron beam, said second aperture having the same axis as said electron beam, said second magnetic element forming a return path for a portion of the flux from said magnetic means.

4. An electron discharge device in accordance with claim 3, wherein a second magnetic means is positioned so as to produce a substantially parallel magnetic field in the region of and substantially parallel to the flow of said electron beam after said electron beam leaves said second aperture, said substantially parallel magnetic field being of strength to maintain said electron beam in its cylindrical path.

5. An electron discharge device comprising means for producing a converging electron beam, a first magnetic element having a first substantially circular aperture therein, said first magnetic element having a substantially paraboloidal surface with a focal point substantially the same as the focal point of said electron beam, a second magnetic element having a second substantially circular aperture therein, said second magnetic element having a substantially paraboloidal surface with substantially the same focal point as the focal point of said electron beam, the said apertures having their axes coincide with the axis of said electron beam, second means for creating a radial magnetic field in said first aperture to cause said electron beam to rotate as it passes therethrough, said second means for creating a magnetic field further creating a magnetic field of substantially confocal paraboloids of revolution with the focal point substantially the same as the focal point of said electron beam.

6. An electron discharge device in accordance with claim 5, wherein said second magnetic element provides a return path for a portion of the magnetic flux between said first and second apertures.

7. An electron discharge device in accordance with claim 6, wherein a third means for creating a magnetic field is positioned around a portion of the path of said electron beam so as to produce a substantially parallel magnetic field in the region of an substantially parallel to the flow of said electron beam after said electron beam leaves said second aperture, said substantially parallel magnetic field being of strength to maintain said electron beam in its cylindrical path.

8. An electron discharge device comprising an

evacuated envelope, a transmission path within said envelope capable of guiding high frequency electrical waves, said transmission path comprising a conductor in the form of an elongated helix, a first means to impress waves to be amplified upon an input end of said transmission path to permit travel of the waves along said path, a second means to couple a load circuit to an output end of said transmission path, a third means to produce and accelerate an electron stream through said helix, said third means comprising a fourth means for generating and accelerating an electron beam, a first magnetic means comprising an element having an aperture therein for creating a magnetic field which has a radial component perpendicular to the axis of said aperture, said electron beam passing through said aperture with its axis substantially parallel to the axis of said aperture to give said electron beam a rotating motion, a second element having a second aperture therein placed at a distance from said first element, said electron beam passing through said second aperture, the adjacent surfaces of said first and second elements being confocal paraboloids of revolution with a focal point coincident with the focal point of the electron beam, said first magnetic means creating a magnetic field of confocal paraboloids of revolution between the said adjacent surfaces of said first and second elements, said paraboloidal magnetic field being of sufficient strength to supply radial accelerating force of the rotating electron beam and to counterbalance the space charge effect of the electron beam.

9. An electron discharge device in accordance with claim 8, wherein said second element is of a magnetic material and provides a return path for a portion of the magnetic flux between said first and second apertures, thus lessening the intensity of the magnetic field in said second aperture and causing said converging electron beam to adapt a cylindrical path of flow.

10. An electron discharge device in accordance with claim 9, wherein a second magnetic means for creating a magnetic field is positioned around a portion of the path of said electron beam so as to produce a substantially parallel magnetic field in the region of and substantially parallel to the flow of said electron beam after said electron

beam leaves said second aperture, said substantially parallel magnetic field being of sufficient strength to maintain said electron beam in its cylindrical path.

5 11. An electron gun comprising a pair of spaced magnetic members having axially aligned apertures therein, the facing surfaces of said members being paraboloidal and respectively convex and concave, means for magnetizing said members to establish a magnetic field therebetween, and means for projecting an electron beam through said apertures in the direction from said concave surface toward said convex surface, said beam projecting means comprising a cathode and electrode means thereadjacent for directing electrons emanating from said cathode along paths converging in said direction.

10 12. An electron discharge device comprising a first and a second magnetic member having axially aligned apertures therein, the surface of said first member facing said second member being substantially paraboloidal, means for projecting an electron beam through said apertures along the axis thereof, and means for producing a magnetic field between said first and second magnetic members.

15 13. An electron discharge device comprising first and second spaced magnetic members having axially aligned apertures therein, the surface of the first of said members facing said second member being substantially paraboloidal, means for producing a converging electron beam, means for projecting said beam through said apertures along the axis thereof, and means for producing a magnetic field between said spaced magnetic members.
